UNITED STATES PATENT OFFICE.

BENJAMIN C. WEBSTER, OF JACKSON, MICHIGAN, ASSIGNOR, BY MESNE ASSIGNMENTS,
TO REYNOLDS SPRING COMPANY, OF JACKSON, MICHIGAN, A CORPORATION OF
DELAWARE.

PULL SOCKET.

Application filed May 4, 1926. Serial No. 106,684.

The invention relates to a chain pull socket.

The object of the present invention is to improve the construction of chain pull sockets and to provide a simple, practical and efficient chain pull socket of strong durable and comparatively inexpensive construction equipped with a switch mechanism for controlling the circuit between the center contact and the wiring terminal thereof adapted to effect a rapid make and break of the circuit and of producing a snap action in the operation of the switch mechanism.

A further object of the invention is to provide a chain socket of this character adapted to effectively separate and protect the wiring terminals so that there will be no liability of arcing or sparking.

With these and other objects in view, the invention consists in the construction and novel combination and arrangement of parts hereinafter fully described, illustrated in the accompanying drawings and pointed out in the claims hereto appended, it being understood that various changes in the form, proportion and minor details of construction, within the scope of the claims, may be resorted to without departing from the spirit or sacrificing any of the advantages of the invention.

In the drawings:

Figure 1 is a side elevation of a chain pull socket constructed in accordance with this invention illustrating the arrangement of one of the wiring contacts.

Fig. 2 is a similar view showing the opposite side of the socket illustrating the arrangement of the other wiring contact.

Fig. 3 is a plan view of the chain pull socket.

Fig. 4 is a reverse plan view of the same.

Fig. 5 is a horizontal sectional view of the device on the line 5—5 of Fig. 1.

Fig. 6 is a longitudinal sectional view approximately on the line 6—6 of Fig. 5.

Fig. 7 is a detail perspective view of the chain guide.

Fig. 8 is a perspective view of the ratchet illustrating the construction of the ratchet mechanism the parts being separated and arranged in juxtaposition.

Fig. 9 is a detail perspective view of the wiring terminal of the screw shell contact.

In the accompanying drawings in which

is illustrated the preferred embodiment of the invention 1 designates an insulating base consisting of a single piece of molded Bakelite or other suitable insulating material and composed of a substantially circular bottom portion and spaced upwardly projecting lugs 2 and 3 located at opposite sides of the center of the insulating base and forming a support for a top or cap plate 4 also constructed of suitable insulating material such as Bakelite. The cap or top plate is secured to the lugs by means of spaced longitudinal screws which extend entirely through the lugs 2 and 3 and the bottom of the insulating base and engage threaded apertures in the opposite sides of a substantially U-shaped plate 5 of the wiring terminal 6 of the screw shell contact 7. The insulating base is provided at its lower face with an approximately U-shaped boss 8 fitting an opening 9 in the top of the screw shell contact 7 whereby the screw shell top is interlocked with the insulating base and is held against rotary movement thereon so that there will be no liability of turning the insulating base or screw shell contact when screwing the plug into a lamp or other insertable device into the shell contact 7. The U-shaped plate 5 of the wiring terminal 6 conforms to the configuration of the boss 8 of the lower face of the insulating base and to the top wall or portion of the screw shell contact and by being engaged by the opposite longitudinal screws the screw shell contact and its wiring terminal are firmly attached to the insulating base. The wiring terminal 6 which is in constant electrical connection with the screw shell contact consists of the said plate 5 and a conductor bar extending upwardly exteriorly of the insulating base adjacent the lug 2 and it is received within a recess 10 of the bottom of the insulating base. The conductor bar or body portion of the wiring terminal 6 is provided at its upper end with a binding screw 11 and it has spaced projections 12 adjacent the binding screw for confining a wire in engagement with the screw.

The center contact 13 which is arranged within the U-shaped boss 8 of the lower face of the insulating base is approximately U-shaped and has a resilient lower portion provided with a substantially concavo-convex enlargement or head 14 for engagement

with the plug of a lamp or other device. The upper portion of the center contact is secured to the insulating base by a tubular rivet 15 which extends through the bottom of the insulating base and through the inner end of a lower switch terminal 16. The lower switch terminal 16 is provided with an outer contact portion 17 which is preferably beveled at one of its side edges as shown and which 5 is located slightly above the bottom of the insulating base. The bottom of the insulating base is provided with a recess 18 to receive the body portion of the lower switch terminal which is angularly bent between its 10 ends as shown to arrange its outer contact portion in proper position to cooperate with a movable switch member 19. The lower stationary switch contact is arranged in spaced relation with an upper stationary switch contact 20 consisting of a plate of suitable conducting metal mounted in a recess 21 of an extension 22 of the lug 2 and provided with an outer upwardly extending portion constituting a wiring terminal 23 equipped 15 with a binding screw 24 and provided with spaced projections 25 for holding a wire in engagement with the head of the binding screw. The upper stationary switch contact projects horizontally from the extension 22 and it is beveled at its lower face at the edge while the lower switch contact is beveled at its upper face at its edge as shown to facilitate the engagement of the movable switch member with the stationary switch 20 contacts.

The movable switch member consists of upper and lower horizontal blades and a vertical connecting portion arranged at the inner or pivoted ends of the blades. The 25 blades are mounted on a vertical pivot 26 which has disposed on it a coiled spring 27 having one end engaging the movable switch member and its other end bearing against the adjacent lug 2 and adapted to urge the movable switch member away from the spaced stationary switch contacts so that as soon as the movable switch member is free to move it will be actuated by the spring 27 to cause a snap action of the switch mechanism in the breaking of the circuit between the wiring terminal 23 and the center contact 13. The switch blades are preferably curved longitudinally as shown and are provided with terminal enlargements 28 which are beveled respectively at their upper and lower faces to engage between the stationary switch contacts.

The connecting portion of the movable switch member is extended to form a projection 29 adapted to be engaged by a rotary controller 30 provided with curved peripheral cams 31 and having intervening recesses 32 the latter being adapted to receive the projecting portion 29 to permit the coiled spring 27 to move the switch blades out of

contact with the stationary switch contacts as clearly illustrated in Fig. 5 of the drawings. The rotary controller 30 which is provided at its upper portion with an annular flange or extension 33 has an annular series of ratchet teeth 34 at its upper face or top which are adapted to be engaged by ratchet teeth 35 of an oscillatory actuator 36. The rotary controller and oscillatory actuator are mounted on a vertical shaft 37 which has disposed on it a coiled spring 38 fitting within the recess of a curved flange 39 of the top plate 4 and having one end engaged with the same. The other end of the coiled spring 38 is engaged with an attaching portion 40 of the oscillatory actuator to which a pull chain 41 is secured. While any suitable flexible connection may of course be employed it is preferable to use the ordinary pull chain composed of spherical links and secured in 5 the attaching portion 40 which is composed of spaced upwardly extending lugs, one of which is slotted at 42 to enable it to be readily engaged by one of the spherical links of the pull chain. The pull chain is adapted to vertically rotate the actuator 36 which imparts a rotary movement of the controller 30. When the chain is pulled its teeth engage with the ratchet teeth 34 of the controller and as soon as the chain is released the spring 38 will move the chain in the opposite direction and cause the actuator 36 to ratchet over the ratchet teeth 34 of the controller. By this construction a step by step rotary movement will be imparted to 100 the controller by the actuator. When one of the cams 31 is carried by the rotary movement of the controller into engagement with the projection 29 of the movable switch member the switch blades will be carried into 105 engagement with the stationary switch contacts and will be maintained in such engagement until the controller is again partially rotated by the actuator to carry one of the recesses 32 in position to receive the 110 projecting portion 29 of the movable switch member and thereby permit the switch member to be carried out of engagement with the stationary switch contacts by the coiled spring 27.

The pull chain extends through the tapered approximately funnel shaped tubular guide 43 located approximately midway between the bottom of the insulating base and the top plate and mounted on a bracket 44 consisting of a vertical bar provided at its ends with horizontal arms 45 extending into grooves or recesses 46 and 47 in the lower face of the top plate and the upper face of the bottom of the insulating base and provided with slots 48 adapted to form resilient fastening devices for securing the arms 45 of the bracket in the recesses or grooves of the insulating base in the top plate. The slotted portions of the arms of the bracket are re- 130

duced as clearly shown in Fig. 7 and the recesses of the insulating base and the top plate thereof conform to the configuration of the arms. The rotary controller which actuates the movable switch member is constructed of a single piece of molded Bakelite or other suitable insulating material and it is spaced from the bottom of the insulating base by a sleeve 49 fitting in a recess or counterbore of the bottom of the insulating base but the sleeve or bushing 49 may be formed integral with the controller and consist of a reduced portion thereof if desired.

The upper stationary switch contact is secured to the upper face or seat of the extension of the lug 2 by means of a screw 50 or other suitable fastening device which is mounted in a suitable bore or opening of the said extension.

20 What I claim is:

1. A pull socket comprising an insulating base having spaced upwardly extending lugs located at opposite sides of the base, the space between the lugs extending entirely across the base to provide a relatively large air space, one of the lugs being provided at one edge with a flange forming a guard or shield and having at the other end an extension forming a seat, a top plate secured to the said lugs, a shell contact secured to the insulating base and having a wiring terminal located at the said flange, a center contact also secured to the insulating base, a lower switch contact mounted upon the base and connected with the center contact, an upper stationary switch contact mounted on the said extension of said lug and having a wiring terminal, and a movable switch member cooperating with the stationary switch contacts.

2. A pull socket including an insulating base having spaced upwardly extending lugs, a shell contact secured to the insulating base and having a wiring terminal located at one side of the said base, a center contact also secured to the base, upper and lower stationary switch contacts located at the opposite side of the base from the said wiring terminal, the lower contact being connected with the center contact and the upper contact being provided with a wiring terminal, a movable switch member composed of spaced knife blades and a connecting portion, the knife blades being adapted to engage with the stationary switch contacts, a rotary controller provided with a peripheral cam arranged to engage the connecting portion of the movable switch member for carrying the knife blades into engagement with the stationary switch contacts, the peripheral cams being spaced apart to provide recesses to receive the connecting portion of the movable switch member to permit the latter to be carried out of engagement with the stationary switch contacts, and a spring for moving the

switch member away from the stationary contacts.

3. A pull socket including an insulating base having spaced upwardly extending lugs, 70 a shell contact secured to the insulating base and having a wiring terminal located at one side of the said base, a center contact also secured to the base, upper and lower stationary switch contacts located at the opposite side of the base from the said wiring terminal, the lower contact being connected with the center contact and the upper contact being provided with a wiring terminal, 75 a movable switch member composed of spaced knife blades and a connecting portion, the knife blades being adapted to engage with the stationary switch contacts, a rotary controller provided with a peripheral cam arranged to engage the connecting portion of the movable switch member for carrying the knife blades into engagement with the stationary switch contacts, the peripheral cams being spaced apart to provide recesses to receive the connecting portion of the movable switch member to permit the latter to be carried out of engagement with the stationary switch contacts, a spring for moving the switch member away from the stationary contacts, ratchet teeth carried by the rotary controller, and an oscillatory actuator provided with ratchet teeth cooperating with the ratchet teeth of the controller to impart a step by step rotation to the same.

4. A pull socket including an insulating base provided with spaced upwardly extending lugs, a top plate mounted on the lugs and having a curved depending flange forming a recess, upper and lower stationary switch contacts mounted on the base, a movable switch member having horizontally swinging switch blades having free terminal portions located at one end of the movable switch member and arranged to engage the stationary switch contacts, said movable switch member being provided at the other end with a projection, a spring for urging the movable switch member away from the stationary contacts, a rotary controller having a series of ratchet teeth and provided with peripheral cams for engaging the said projection of the movable switch member to carry the switch blades into engagement with the stationary contacts, an oscillatory actuator having ratchet teeth for imparting a step by step rotation to the controller, a coiled spring housed within the recess of the said curved flange and bearing against the same and against the actuator for moving the same in one direction, and a pull chain for moving the actuator in the opposite direction.

5. A pull socket including a base, a shell contact secured to the base and having a wiring terminal, a center contact also secured to the base, upper and lower stationary switch contacts, the lower contact being

connected with the center contact and the upper contact being provided with a wiring terminal, and a horizontal movable switch member arranged to swing into and out of engagement with the stationary switch contacts, a rotary controller provided with means for actuating the movable switch member and having ratchet teeth, and an oscillatory actuator having radially disposed arms bevelled to form teeth for engaging the ratchet teeth of the controller, one of the arms being provided with an integral vertically disposed approximately U-shaped portion open at the top to permit the links of a chain to be introduced between the sides of the U-shaped portion and engaged with the same.

6. A pull socket including an insulating base having spaced upwardly extending lugs, a shell contact secured to the insulating base and having a wiring terminal located at one side of the said base, a center contact also secured to the base, upper and lower stationary switch contacts located at the oppo-

site side of the base from the said wiring terminal, the lower contact being connected with the center contact and the upper contact being provided with a wiring terminal, a movable switch member pivotally mounted on the base and having upper and lower horizontally swinging knife blades cooperating with the stationary switch contacts and located at one end of the movable switch member, the movable switch member being provided at the other end with a laterally extending projection, a coiled spring connected with the movable switch member for urging the same away from the stationary switch contacts, a rotary controller provided with means for engaging the said projection for moving the switch member into engagement with the stationary switch contacts and ratchet mechanism including a pull chain for imparting a step by step rotary movement to the controller.

In testimony whereof I have hereunto set my hand.

BENJ. C. WEBSTER.
